(57) **CLAIM**

The ornamental design for a bottle, as shown and described.

DESCRIPTION

FIG. 1 is a perspective view of a bottle showing my new design;

FIG. 2 is another perspective view thereof;

FIG. 3 is a front elevational view, the rear elevational view, the left side view and the right side view are identical;

FIG. 4 is a top plan view thereof;

FIG. 5 is a bottom plan view thereof;

FIG. 6 is a partial enlarged view thereof according to the broken circle labeled "FIG. 6" in FIG. 1;

FIG. 7 is an exploded perspective view of FIG. 1; and,

FIG. 8 is another exploded perspective view thereof.

The broken lines in the figures are for the purpose of illustrating portions of the bottle that form no part of the claimed design.
